(57) **CLAIM**

The ornamental design for a hammer mill spacer and lock collar holder, as shown and described.

DESCRIPTION

FIG. 1 is a top, front, right perspective view of a hammer mill spacer and lock collar holder;

FIG. 2 is a bottom, rear, left perspective view of a hammer mill spacer and lock collar holder;

FIG. 3 is a front view of a hammer mill spacer and lock collar holder;

FIG. 4 is a rear view of a hammer mill spacer and lock collar holder;

FIG. 5 is a right-side view of a hammer mill spacer and lock collar holder;

FIG. 6 is a left-side view of a hammer mill spacer and lock collar holder;

FIG. 7 is a top view of a hammer mill spacer and lock collar holder;

FIG. 8 is a bottom view of a hammer mill spacer and lock collar holder;

FIG. 9 is a top, front, right perspective view of a hammer mill spacer and lock collar holder;

FIG. 10 is a bottom, rear, left perspective view of a hammer mill spacer and lock collar holder;

FIG. 11 is a front view of a hammer mill spacer and lock collar holder;

FIG. 12 is a rear view of a hammer mill spacer and lock collar holder;

FIG. 13 is a right-side view of a hammer mill spacer and lock collar holder;

FIG. 14 is a left-side view of a hammer mill spacer and lock collar holder;

FIG. 15 is a top view of a hammer mill spacer and lock collar holder; and,

FIG. 16 is a bottom view of a hammer mill spacer and lock collar holder.

A description of the appearance of the article is as follows: any shading and cross-hatching are not features of the design but are utilized to illustrate the surface contours of the hammer mill spacer and lock collar holder design in the drawings. The dash-dash broken lines in FIGS. 1-6, 8, 9-14, and 16 depict portions of the hammer mill spacer and lock collar holder that form no part of the claimed design. The dash-long dash broken lines in FIGS. 1-6 and 9-14 depict the bounds of the claim and form no part of the claimed design.

1 Claim, 12 Drawing Sheets
